SEPARABLE FRAME FOR HANDBAGS OR
THE LIKE

Clyde D. Buckley, Needham, Mass., assignor to
United-Carr Fastener Corporation, Cambridge,
Mass., a corporation of Massachusetts

Application June 11, 1938, Serial No. 213,249

2 Claims. (Cl. 150—29)

This invention relates to improvements in bag frame structures.

One of the objects of my invention is to provide a bag frame structure comprising a purse frame and an outer frame with the hinging devices at opposite ends of the frames of simple and inexpensive form and constructed in a way to enable the purse frame to be removably secured to the outer frame with but a minimum, 10 if any, use of the natural resiliency of either frame.

In the drawing, which represents a preferred embodiment of my invention:

Fig. 1 is a fragmentary plan view of a handbag frame structure including an outer frame having an inner purse frame removably secured thereto;

Fig. 2 is an enlarged longitudinal section showing the hinging device at the left-hand end of the frame structure looking at Fig. 1 of the drawing;

Fig. 3 is an enlarged longitudinal section showing the hinging device through the right-hand end of the frame structure looking at Fig. 1 of the drawing;

Fig. 4 is an enlarged plan view of the hinge device at the right-hand end of the purse frame looking at Fig. 1 of the drawing and showing a spring means assembled therewith; and

Fig. 5 is an end view of the hinge assembly shown in Fig. 4 looking from the left.

Referring to the drawing, Fig. 1 shows a handbag frame structure including an outer frame 1 and an inner purse frame 2 removably secured to the outer frame 1 through my improved hinging device. The outer frame 1 comprises a pair of frame members having a set of leg portions 3 and 4 at opposite ends of the frame. The purse frame 2 comprises a pair of frame members having a set of channel-shaped leg portions 5 and 6 at opposite ends of the frame. Relatively flat ear-shaped portions 7 and 7' are provided at the outermost ends of the legs of each of the sets 5 and 6 hinged together by a hollow rivet 8, as most clearly shown in Figs. 2 and 3. Each of the channel-shaped frame members of the frame 2 has a back wall 9 and a pair of spaced side walls 10—10' (Fig. 5) which extend angularly from the base 9 in a direction opposite the adjacent set of legs 3 and 4 of the outer frame 1.

Referring in detail to my improved hinging construction, I have chosen to construct the outer frame so that the free end of the leg 3 is provided with an integral hollow bearing 11 and the free end of the leg 4 is provided with 55 a relatively flat ear-shaped element 12 having

an opening 13 therethrough (Figs. 2 and 3) in substantial alignment with the bore of the hollow bearing 11. The portions 11 and 12 are held together in hinged relation in each end of the frame 1 by hollow rivets 14 and 14'. Each of 5 the rivets 14 and 14' presents an opening 15 at its inner end for receiving an attaching portion of respective cooperating pins at opposite ends of the purse frame 2, as will be described.

As a means for hingedly securing the purse frame 2 to the outer frame 1, I have assembled solid pin members 16 and 17 with respective opposite ends 18 and 19 of the frame 2. As the removable feature of my improved bag frame structure is more efficiently carried out if the pin members 16 and 17 have slightly different relative dimensions, I prefer to describe them in that manner although it is possible that successful engagement and disengagement of the purse frame with the outer frame could be effected if the pin members at opposite ends of the purse frame were constructed with identical dimensions.

The pin member 16 (Fig. 2) is preferably of solid construction and comprises a body portion 20 and a shank portion 21 of reduced diameter projecting beyond one end of the body portion 20 so as to form a shoulder 22. An attaching portion 23, having a smaller diameter than the body portion, projects beyond the other end of the body portion from the shank 21 forming a shoulder 24. The pin member 16 is assembled with the legs 5 and 6 at the end 18 of the frame 2 through inserting the shank portion 21 through the hollow rivet 8 and heading the shank portion over as at 25 on an opposite side of the ear-shaped elements 7 and 7' from the shoulder 22. The pin member 17 has a body portion 26 and a shank portion 27 of smaller diameter than the body portion and extending beyond one end 30 of the body portion forming a shoulder 28. An attaching portion 29, which is preferably relatively longer than the attaching portion 23 of the pin member 16, extends beyond the other end of the body portion 26 from the shank portion 27. The attaching portion 29 has a smaller diameter than the body portion 26 forming a shoulder 30. The pin member 17 is assembled with the legs 5 and 6 at the end 19 of the frame 2 through inserting the shank portion 27 through the hollow rivet 8 and heading the shank over 40 as at 31 on an opposite side of the ears 7 and 7' from the shoulder 28.

As a means for assembling the purse frame 2 with the outer frame 1 without the necessity for 50

55

any substantial springing of either one of the frames, a coil spring 32 is assembled with the pin member 17 and disposed around the body portion 26 and at least a portion of the attaching portion 29 thereof. The coil spring 32 is maintained in assembly with the pin member 17 through means of a relatively straight free end portion 33 which is sprung over a side wall 10 of one of the frame members of the purse frame so as 10 to be disposed within the channel of the respective frame member in engagement with one of the walls thereof, as most clearly shown in Fig. 5. Thus the coil spring is quickly and easily assembled with the pin member 17 so as to carry out 15 the function of the same, as will be described. It will be noticed that the coil spring extends substantially to the outermost free end of the attaching portion 29 whereby the spring may be compressed upon entrance of the attaching portion 29 into the rivet 14' of the outer frame.

Assembly of the purse frame 2 with the outer frame 1 is a relatively simple matter and may be accomplished without the necessity for bending either one of the frames sufficiently to destroy 25 the shape of the same. In carrying out this action, the outermost free end of the attaching portion 29 of the pin member 17 is inserted into the hollow rivet 14' at one end of the outer frame member. Then pressure is exerted upon the purse 30 frame 2 forcing the attaching portion 29 into the hollow rivet 14' a sufficient distance to enable the attaching portion 23 of the pin member 26 to seat itself within the hollow rivet 14 at the other end of the outer frame 1. As the attaching portion 29 is forced into the rivet 14', the coil spring 32 is compressed and after the attaching portion 23 of the pin 16 has been moved into the respective hollow rivet 14, the coil spring expands to move the shoulder 24 of the pin member 16 35 against the inner end of the rivet 14 (Fig. 2) whereby the purse frame will be hingedly engaged with the outer frame. As a result of the fact that the distance between the shoulder 30 of the pin member 17 and the outermost free end of the 40 attaching portion 29 is greater than the distance between the shoulder 24 and the outermost free end of the attaching portion 23 of the pin member 16, a portion at the free end of the attaching portion 29 remains within its respective hollow rivet 14' so as to prevent disengagement of 45 the purse frame from the outer frame except by reversal of the action hereinabove described.

Thus by my invention I have provided a simple and inexpensive method for springing a purse frame into engagement with an outer frame. Furthermore, by my improved method the frame members are subjected to no more than a minimum amount of strain during assembly one with another.

Although I have illustrated and described a preferred embodiment of my invention, I do not

wish to be limited thereby because the scope of my invention is best defined by the following claims.

I claim:

1. A frame for a handbag or the like container comprising an outer frame and a removable inner frame, each of said frames comprising a pair of frame members having sets of adjacent leg portions hinged together at their ends, each of the frame members of one pair being channel-shaped, the ends of a set of leg portions of said last-mentioned pair having a pin member projecting therefrom, said pin member having an attaching portion at its end away from said ends for entrance into a hollow member of the other frame, a coil spring assembled with said pin member and disposed around said attaching portion, said spring having a free end portion disposed within the channel of one of said channel-shaped frame members whereby said spring is maintained in assembly with said pin member, and said other pair of frame members having a hollow member adapted to receive the attaching portion of said pin member while compressing said spring whereby said inner frame may be secured to said outer frame by movement of one part of one frame relative to a part of the other frame. 15

2. A two-part bag frame comprising an outer frame and a removable purse frame, said outer frame comprising a pair of frame members having a set of leg portions at each end, the ends of each set of leg portions being hinged together by a hollow rivet, said purse frame comprising a pair of frame members having a set of leg portions at each end, each set of leg portions being hinged together at their free ends and a pin member assembled with the free ends of each of said sets, each of said pin members having a body portion disposed on one side of the ends of each of said respective sets of said leg portions 35 of said purse frame, a shank portion of smaller diameter than said body portion extending through said last-mentioned ends and headed over on the other side of said ends from said body portion and an attaching portion at the 40 other end of said body portion from said shank of smaller diameter than said body portion, said attaching portions defining spaced shoulders on said body portions of said pin members whose normal spacing is less than the distance between 45 the hollow rivets of the outer frame, a coil spring assembled with one of said pin members and having a portion disposed around said attaching portion, one of said hollow rivets of the outer frame being adapted to receive the attaching portion 50 of said pin member having said spring while compressing said spring whereby said purse frame may be secured to said outer frame by movement of the purse frame relative to the outer frame without springing either of the frames. 55
